UNITED STATES PATENT OFFICE.

JAMES A. TRANE, OF LA CROSSE, WISCONSIN.

STEAM-TRAP.

SPECIFICATION forming part of Letters Patent No. 286,506, dated October 9, 1883.

Application filed July 27, 1883. (No model.)

To all whom it may concern:

Be it known that I, JAMES ALEXANDER TRANE, of La Crosse, in the county of La Crosse and State of Wisconsin, have invented 5 a new and Improved Steam-Trap, of which the following is a full, clear, and exact description.

My invention consists of the escape-pipe of the trap, extended nearly to the bottom inside, 10 to trap the steam by the water of condensation, and having a valve which, before the water falls to the end of the pipe, is closed by a float, and remains closed until the water rises to about two-thirds of the height of the chamber, when it is opened by the float, to allow the 15 water to be forced out through the waste-pipe by the steam, making an efficient and reliable trap through which the steam cannot waste when the water falls, all as hereinafter fully 20 described.

Reference is to be had to the accompanying drawings, forming part of this specification, in which similar letters of reference indicate corresponding parts in all the figures.

25 Figure 1 is a longitudinal sectional elevation of my improved steam-trap. Fig. 2 is a transverse section taken on the line $x x$ of Fig. 1, and Fig. 3 is a detail of the regulating-cock in section.

30 I make a strong trap-case, a , preferably of cast metal, having one removable head, b , and provided with legs c , for standing on the floor, said case being capable of standing boiler-pressure of steam, and fit said case with the 35 inlet-pipe d and waste-pipe e for the water, said waste-pipe extending nearly to the bottom of the case, and in this case I fit a cock, f , or valve, which has for its stem a triangular plate, g , having a curved slot, h , in which 40 two stop-pins, i , are fitted adjustably, so as to be shifted to set them at different distances apart. On the center j of said valve-stem a lever, k , of a float, l , is pivoted, which plays

between the stops i as the water rises and falls. The lower stop is to be so adjusted that 45 the float will close the valve when it descends by the fall of the water, and shut off the escape through pipe e just before the water falls to the lower end of the pipe e . The other stop is to be set according to the height it is desired that the water shall rise before opening the pipe, which I prefer to be about two-thirds 50 of the height of the case.

It will be seen that by this improved apparatus the water cannot in any case be forced 55 out, so that the steam will blow through, as it does in some other traps.

On the top of the case is an air-cock, l , and at the bottom a waste-cock, m , to draw off the water in cold weather when the trap is not in 60 use.

I do not abandon or dedicate to the public any patentable feature set forth herein and not hereinafter claimed, but reserve the right to claim the same either in a reissue of any 65 patent that may be granted upon this application or in other applications for Letters Patent that I may make.

Having thus described my invention, what I claim as new, and desire to secure by Letters 70 Patent, is—

The combination, in a steam-trap, of the waste-pipe e , extending nearly to the bottom of the chamber, the regulating-cock f in said pipe, and the float l , the arm of said float acting on the cock by the adjustable stops i of plate g , closing it before the water falls to the lower end of the pipe e , and allowing it to remain closed until the water rises a predetermined distance above said end of the pipe, substantially as described. 75 80 85

JAMES ALEXANDER TRANE.
